UNITED STATES PATENT OFFICE.

LOUIS WILPUTTE, OF NEW ROCHELLE, NEW YORK, ASSIGNOR OF TWO-THIRDS TO
ALICE A. WILPUTTE, OF NEW ROCHELLE, NEW YORK.

STANDPIPE CONNECTION.

1,414,492.

Specification of Letters Patent. Patented May 2, 1922.

Application filed January 19, 1920. Serial No. 352,529.

To all whom it may concern:

Be it known that I, LOUIS WILPUTTE, a citizen of the United States, and a resident of New Rochelle, in the county of Westchester and State of New York, have invented certain new and useful Improvements in Standpipe Connections, of which the following is a specification.

The general object of my present invention is to provide an improved valve arrangement especially devised for use in the stand pipe connections from the coking chambers to the gas collecting main of a by-product coke oven plant.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described a preferred embodiment of the invention.

Of the drawings:

Fig. 1 is a sectional elevation of a portion of a by-product coke oven battery;

Fig. 2 is a plan of a portion of the apparatus shown in Fig. 1;

Fig. 3 is a sectional elevation of the apparatus shown in Fig. 2; and

Fig. 4 is a plan on a small scale of a portion of the coke oven battery.

In the drawings A represents the coking chambers of a by-product coke oven battery AA of a well-known type, and B the stand pipe connections, one from each chamber A to the usual gas collecting main C which extends longitudinally of the oven battery AA and transversely of the individual coking chambers A. Each of the stand pipe connections B, as shown, comprises a portion extending vertically upward from the oven structure, and a horizontal portion which extends over the collecting main and is provided with a port B' in its under side opening into the collecting main through the top wall of the latter. Associated with the port B' is a valve D in the form of a disc which may well be made of iron or steel plate, and is riveted or otherwise secured to the lower end of a valve stem D' which passes upward through a removable head B³ normally closing an opening in the stand pipe

connection B above the port B'. The valve 55 mounting thus provided for each valve D permits the movement of the valve back and forth between its open position shown in dotted lines in Figs. 1 and 3, and its closed position shown in full lines in Fig. 1. In 60 its open position, each valve D is located in the collecting main C at such a distance below the top wall of the latter that it does not impede the flow of gas into the main from the corresponding stand pipe. In its 65 closed position, each valve D lies in the upper portion of the port B' which is also the most restricted portion of the port B' when the latter is of the preferred tapered or 70 conical form shown in the drawing. The valve disc D need not fit closely in the portion of the port B' occupied by the valve in its closed position, and I expect, in practice, to make each valve disc D a sixteenth of an 75 inch or so less in diameter than the portion of the port B' occupied by the valve in the closed position of the latter. Each valve stem D' preferably has affixed to it an external motion limiting collar D² which rests on the head B³ in the open position of the 80 valve, and bears against the guide yoke B⁴ in the closed position of the valve. Any suitable jack or other mechanism may be employed for raising and lowering the valve. For example, as shown, a carriage E, running 85 on rails C' and C² fixed to the side of the main C, may be provided with a hoisting winch E' for raising and lowering a hook E² adapted to engage a pin or crossbar D³ connected to the upper end of the valve 90 stem D'.

Means are provided for spraying tar or a mixture of tar and ammonia liquor into the collecting main through each port B'. For this purpose, I provide in the construction 95 shown, a tar supply pipe F running alongside the main C and provided with a branch F' for each port B'. Advantageously each branch F' is connected into a T G which is threaded into a port B⁶ formed in the wall of the corresponding port B'. The port B⁶ opens into the port B' just below the valve D when the latter is in its closed position, and the port B⁶ is downwardly inclined 100 (see Fig. 3) so that, with the valve in its open position, the liquid discharged through each port B⁶ will wash the upper side of the corresponding valve D. The T G is pro- 105

vided with a cleanout opening, normally closed by a plug G'.

In the practical intended use of the apparatus shown, the standpipe connections from the various coking chambers of the coke oven battery are in free communication with the collecting main C at all times except that at the end of each coking operation in a coking chamber A, of sixteen to twenty-10 four hours or so, the corresponding valve D is closed for half an hour or so. The gases that pass through each stand pipe are hot and contain tars which condense in part as the gases cool in flowing through the hot, 15 but air cooled, stand pipe connections. There is a constant tendency to the deposit of pitch and carbon, formed by the decomposition of the hot tars, on the walls of the piping. Such deposits bake and adhere with 20 great tenacity to the stand pipe walls. The adherence of the pitch and carbon to the bottom portion of the collecting main is largely prevented by maintaining a constant flow of a flushing liquid stream of tar or 25 tar and ammonia liquor through the main. All the tar or tar and ammonia liquor required for flushing the main C may be supplied by the branches F', or a part of this liquid may be injected into the end of the 30 main by a branch F² as shown in Fig. 4. F³ represents the pipe through which the flushing liquid is withdrawn.

With the novel arrangement disclosed each valve D, when in its open position, is 35 constantly bathed in the flushing liquid discharged by the corresponding port B⁶ and eventually forming a part of the flushing liquid stream flowing through the main C. The valves D are thus protected against the 40 deposit of pitch and carbon on them while in their open positions. Each time a valve D is moved into its closed position it cuts through the deposit of pitch and carbon on the wall of the port B', thus effectually cleaning the latter, and at the same time cuts a seat for itself fitting perfectly about the periphery of the valve. The material thus cut from the wall of the port B' and collecting above the valve D may be removed when the valve is 45 50 in its closed position by a tool or implement inserted through the clean-out door B'. In normal operation each port B' will be sealed when the corresponding valve D is moved into its closed position by the pitch and carbon deposit between the valve and the metallic wall of the port B'.

In any case in which the pitch and carbon deposit does not provide a gas-tight seal, such a seal is insured by the liquid, though 60 somewhat viscous, tar or tar and ammonia liquor layer which the valve D will carry on its upper side. As the valve D moves into its closed position it first approaches and then passes the tar inlet B⁶ and in consequence a considerable amount of tar will be 65

carried on the top of the valve D when it reaches its closed position. This tar will run into and seal any open joint which may exist, in practice, between the periphery of the valve and the deposit coated wall of the 70 port B'. It should be explained that the difference between the gas pressure in the main C and the pressure above the valves D when the latter are closed is very small, usually about equal to a head of four or five 75 millimeters of water. To prevent the tar on the tops of the valve D' from running over any considerable portion of the bottom of the horizontal portions of the corresponding stand pipes, I preferably form an inclined rim B⁸ about the upper margin of each port B'. Those skilled in the art will know that each stand pipe B is put in free communication with the atmosphere by the opening of its door B⁹ during practically 85 the entire period in which the corresponding valve D is closed.

The truck E may be moved lengthwise of the battery on the rails C' and C² to bring the winch hook E' in position for engagement with first one and then another of the valve stems D' as the various coking chambers are discharged and recharged in regular turn. Should a valve D stick in its seat when the time comes to open it, the valve 95 may be forced to its open position by hammer blows on the upper end of the valve stem D'.

The improved valve arrangement possesses numerous important advantageous 100 characteristics from a practical standpoint. It is relatively inexpensive to construct as the parts are few, light in weight and require a minimum of machining. In case the valve proper becomes bent or otherwise 105 injured, it may be replaced easily and at a very small expense. If necessary or desirable each valve D may be rotated in its seat to facilitate the removal through the clean-out door B' of pitch and carbon deposits 110 cut from the wall of the port B' in the movement of the valve into its closed position. The provisions described for delivering a jet of tar or tar and ammonia liquor on the top of each valve disc when in its open position not only keep the valve discs clean and provide them with sealing material when closed, but also form simple and effective means for supplying the main C with the necessary flushing liquid. It is never necessary 115 in normal operation to interrupt the discharges through the various ports B⁶.

While in accordance with the provisions of the statutes I have illustrated and described the best form of my invention now 125 known to me, it will be apparent to those skilled in the art that changes may be made in the apparatus disclosed without departing from the spirit of my invention as set forth in the appended claims and that in 130

some cases certain features of my invention may be used to advantage without a corresponding use of other features.

Having now described my invention, 5 what I claim as new and desire to secure by Letters Patent, is:

1. The combination with a collecting main having an inlet port of a valve movable through said port and substantially 10 closing the port when in the latter and a mounting for said valve permitting its movement between an open position in which the valve is located within the main and a closed position in which the valve is located 15 in said port.
  2. The combination with a collecting main of a stand pipe connected thereto comprising a portion extending over the collecting main and communicating with the 20 latter through a port opening through the top wall of the main and a valve member movable back and forth between an open position in which it is located within the main and a closed position in which it is 25 located in the port.
  3. The combination with a collecting main having an inlet port of a valve movable between an open position in which the valve is located within the main and a 30 closed position in which the valve is located in said port and means for bathing said valve with a liquid while in its open position.
  4. The combination with a collecting 35 main of a stand pipe connected thereto comprising a portion extending over the collecting main and communicating with the latter through a vertically elongated port opening through the top wall of the main 40 and a valve member movable back and forth between an open position in which it is located within the main and a closed position in which it is located in an upper portion of the port and means comprising 45 an orifice in the side wall of said port below the valve when the latter is in its closed position for discharging liquid into the main, said liquid falling on the valve when the latter is in its open position.
  5. The combination with a collecting 50 main of a stand pipe connected thereto comprising a portion extending over the collecting main and communicating with the
- latter through a port opening through the top wall of said main and formed with an opening above said port, a head normally closing the last mentioned opening, a valve stem movably mounted in said head, a valve disc secured to the inner end of said stem and movable through said port but substantially closing said port when in the latter, said connection being formed with a cleanout door adjacent the said port, and being formed with a depression in its under side into which said port opens. 60
6. The combination with a collecting main of a stand pipe connected thereto comprising a portion extending over the collecting main and communicating with the latter through a vertically elongated port opening through the top wall of said main and formed with a depression in its under side into which said port opens, a valve movable between a closed position in which the valve is located in said port and an open position in which it is located in said main and means for bathing said valve with a liquid while in its open position. 65
7. The combination with a collecting main of a stand pipe having an inlet port, a valve member movable through said port, and means normally limiting the movement of said valve between an open position in which it is located within the main and a closed position in which it is located in the port. 70
8. The combination with a collecting main of stand pipes connected thereto and each comprising a portion extending over the collecting main and communicating with the latter through a port opening through the top wall of the main and a valve member for each of said ports movable back and forth between an open position in which it is located within the main and a closed position in which it is located in the corresponding port and means for discharging a flushing liquid into the main adjacent each of said ports and so as to bathe the upper side of said valves when the latter are in their open positions. 75

Signed at New York, in the county of New York and State of New York, this 17th day of Jan. A. D. 1920.

LOUIS WILPUTTE.
